UNITED STATES PATENT OFFICE

159,175

BOAT HULL

Holmes A. Thurmond, Shreveport, La.

Application February 23, 1949, Serial No. 1,009

Term of patent 14 years

(Cl. D71—1)

To all whom it may concern:

Be it known that I, Holmes A. Thurmond, a citizen of the United States, residing at Shreveport, county of Caddo, State of Louisiana, have invented a new, original, and ornamental Design for Boat Hulls, of which the following is a specification, reference being had to the accompanying drawings, forming a part thereof.

Fig. 1 is a perspective view taken from above and from the rear of a boat hull embodying the new design; and

Fig. 2 is a side perspective view of the ornamental design for a boat hull taken from the front.

Fig. 3 is a top plan view of the ornamental design for a boat hull.

I claim:

The ornamental design for a boat hull, substantially as shown.

HOLMES A. THURMOND.
